CLAIM

The ornamental design for a curling tong heater, as shown and described.

DESCRIPTION

FIG. 1 is a left, front perspective view of the curling tong heater of my new design, in which the unshaded inner areas bounded by the oblong and circular outlines in FIG. 1 areas inside do not form part of the claimed design.

FIG. 2 is a left, rear perspective view thereof;

FIG. 3 is a bottom plan view thereof; and,

FIG. 4 is a right side elevational view thereof, the left side elevational view being a mirror image thereof.
